UNITED STATES PATENT OFFICE.

ALEXANDER AIMWELL CANTIN, OF NEW YORK, N. Y.

DESIGN FOR AN OPENWORK CORNICE.

43,839.

Specification for Design.

Patented Apr. 15, 1913.

Application filed January 25, 1913. Serial No. 744,249. Term of patent 14 years.

To all whom it may concern:

Be it known that I, ALEXANDER AIMWELL CANTIN, a citizen of the United States of America, residing at New York city, borough of Manhattan, county and State of New York, have invented a new, original, and ornamental Design for an Openwork Cornice, of which the following is a specification, reference being had to the accompanying drawing, forming part thereof,

which is a bottom view of an openwork cornice showing my new design.

I claim:

The ornamental design for open work cornice, as shown.

ALEXANDER AIMWELL CANTIN.

Witnesses:

EUGENE J. CANTIN,
M. G. CRAWFORD.
